MOPSTICK HEAD

Filed April 14, 1926

Patented Oct. 2, 1928.

1,685,796

UNITED STATES PATENT OFFICE.

JOSEPH WILMER WOHLHETTER, OF IRVINGTON, NEW JERSEY, ASSIGNEE TO KEY-STONE STAMPING CORPORATION, A CORPORATION OF NEW JERSEY.

MOPSTICK HEAD.

Application filed April 14, 1926. Serial No. 101,902.

My invention relates to that class of mopstick heads which comprises a metallic body portion provided with a transverse groove along the end thereof and a clamping wire or bail adapted to fit within said groove and hold the mop in place. The grooves in the cross heads have been a source of considerable trouble, due to the fact that the flanges in the metal which form said grooves are apt to become bent out of shape. If these flanges are bent inwardly or toward each other a locking of the clamping wire will take place, and if they are bent outwardly, there is danger of the clamping wire slipping out of the groove and off the head.

An object of the invention is to provide a construction of mopstick head in which great rigidity in the groove-containing portion thereof is attained, and in which danger of bending the walls of the groove is reduced to a minimum.

A further object of the invention is to provide a novel construction of mopstick head in which the parts thereof may be assembled and held in operating position without the use of rivets, tongues and other analogous securing devices.

Other objects of the invention will herein-after appear and the novel features thereof will be set forth in the claims.

In the drawings forming part of this specification:

Fig. 1 is an elevation of a mopstick with my improved head applied thereto;

Fig. 2 is a top plan view of the head shown disconnected from the mopstick;

Fig. 3 is a section on the line 3—3 of Fig. 2;

Fig. 4 is an end view of the head;

Fig. 5 is a face view of one of the blanks from which the body portion of the head is formed;

Fig. 6 is a similar view of the same with the socket-forming portions stamped therein;

Fig. 7 is a face view of the blank from which the channel-forming member is produced.

Like reference numerals indicate like parts in the different views.

The mopstick 1 has been shown as having applied to the lower end thereof a metallic cross head 2, having a transversely extending groove or channel 3 in the lower end thereof and a socket portion 4 within which the end of the mopstick 1 fits. Cooperating with these

parts is a clamping wire or bail 5, designed to clamp the mop 6 in the groove 3, and connected at its upper end to a lever 7 fulcrumed upon one of the convolutions of a coil spring 8 which surrounds the mopstick 1 and is attached thereto and to the head 2 by means of a staple 9, or other analogous securing device. The foregoing parts correspond with those shown in the patent to Conchar, #1,508,925, dated September 16, 1924.

My improvements have to do with the construction of the head 2. As shown, it comprises a body portion 10 and channel-forming portion 11. The body portion 10 is preferably made from a blank 12 of sheet metal having a central longitudinally extending slit 13 therein, and an opening 14. This blank is stamped to produce the socket-forming portions 15 and 16 and the outwardly extending flanges 17 and 18. It is then bent along the line of the slot 13 to complete the formation of the socket 4, to provide two parallel strips of material 19 which lie in close contact with each other and to provide the outwardly directed flanges 17 and 18. Heretofore, the head would be completed by securing the strips 19 together and utilizing the flanges 17 and 18 as the groove in which the clamping wire 5 fits, but according to my invention I employ an additional part 11, which I have termed a channel-forming portion. This is produced from a blank 20 by first curving the same longitudinally to form the groove or channel 3 and afterwards bending the side portions of said blank back upon themselves to form the flanges 21, 22, which are substantially parallel to the walls of the groove 3. These flanges, however, are slightly separated along their adjacent edges. The blank 20 is longer than the body portion 10 and at the ends thereof recesses 23 are formed. The extent of these recesses is increased, after the parts have been assembled, by bending upwardly the edges thereof to form the retaining end flanges 24. These flanges engage the ends of the flanges 17, 18. The notched recesses formed by bending upwardly and inwardly the flanges 24 provide for the passage of the parallel portions of the clamping bail 5 at the ends of the cross head and act as guides therefor. When the blank 12 is folded to form the body portion of the head, stops 25 are formed in the lower part of the socket 4 by bending inwardly from opposite sides portions of the metal of said blank.

In assembling the parts of the head 2, above described, the flat portions 19 of the blank 12, after the latter has been folded upon itself, are held in contact with each other. The channel-forming part 11 is then placed upon the body portion with the flanges 17 and 18 lying in the space between the flanges 21 and 22 and the upper side of the groove 3. At this time the flanges 21 and 22 are substantially parallel with each other. They are afterwards turned inwardly, to their final positions, as shown in Figs. 2 and 4, and the flanges 24 are turned up. The two parts of the cross head are thus firmly and securely united and held permanently in place without the use of rivets, tongues or other analogous securing devices. And the cross head produced by the body 10 and channel-forming portions 11 is extremely rigid and unyielding throughout. The channel or groove 3 is formed by a double thickness of metal so shaped as to prevent bending or curling from ordinary jars or blows, and in which spreading of the side walls of the groove is effectually prevented. The two parts of the head tend to reinforce each other and produce a structure which is extremely strong and unyielding.

30 I claim:

1. A mop head comprising a body portion made up of parallel plates having opposed edges bent outwardly to form flanges, and a member cooperating with said flanges having a groove or channel extending throughout the length thereof and formed with side flanges which embrace the flanges on the body portion.

2. A mop head made in two parts, one of

which comprises a body member provided with outwardly extending flanges, and the other of which comprises a re-inforcing member provided with inwardly extending flanges cooperating with the flanges on the first part to secure the two members together.

3. A mop head made in two parts, one of which comprises a body member provided with outwardly extending flanges, and the other of which comprises a re-inforcing member provided with a groove and inwardly extending flanges cooperating with the flanges on the first part to secure the two members together and is also provided with recesses at the opposite ends of said groove.

4. A mop head made in two parts, one of which is provided with opposed outwardly extending flanges, and the other of which is provided with a groove and inwardly extending flanges cooperating with the flanges on the first part, and is also provided with recesses at the opposite ends of said groove and upturned flanges around said recesses.

5. A mop head comprising a body portion having parallel side members provided with outwardly extending flanges, and a member cooperating with said flanges having a groove formed therein throughout the length thereof, and also having side flanges embracing the flanges of said body member, the said member being further provided with recesses at the opposite ends of said groove and with upturned flanges surrounding said recesses engaging the ends of the flanges of said body portion.

In witness whereof, I hereunto subscribe my signature.

JOSEPH WILMER WOHLHIEDER.
